DONALD A. QUARLES, OF ENGLEWOOD, NEW JERSEY, ASSIGNOR, BY MESNE ASSIGNMENTS, TO WESTERN ELECTRIC COMPANY, INCORPORATED, A CORPORATION OF NEW YORK.

SUPERVISORY SYSTEM.

Application filed February 14, 1925. Serial No. 9,157.

This invention relates to telephone transmission systems, and especially to supervisory systems for use by repeater attendants.

5 An object is to provide simple and efficient methods and means for monitoring and talking on transmission systems, especially at repeaters.

In the specific forms of the invention 10 shown in the accompanying drawings, a number of features contribute to the attainment of this object. For instance, when the repeater attendant has his transmitter connected for talking in one direction to the 15 exclusion of the other, on the output side of the repeater amplifier for the one direction, he may have his receiver connected for amplified receiving through the repeater, from the line section to which his transmitter is in talking relation, and, moreover, 20 without permitting excessive side tone in his receiver; when monitoring, he may have his receiver switched to the low impedance side of his transmitter transformer, to decrease 25 the transmission loss occasioned by monitoring; and when monitoring and talking through both of the repeater output 30 transformers, he may have a resistance connected across his receiver to prevent undesired reaction between those transformers, as pointed out hereinafter. Further objects and 35 features will be made apparent in the following description in connection with the drawings, wherein:

Fig. 1 shows an application of the invention to a two-wire transmission system at a 22-type repeater; Figs. 2 to 8 are simplified diagrams indicating seven different circuit conditions of the repeater attendant's 40 supervisory apparatus or telephone set with regard to the relationship between its parts and its relationship to the repeater or the circuit with which it is adapted to cooperate, any of these seven circuit conditions being 45 obtainable at will; Fig. 9 shows a four-wire repeating system having therein a four-wire repeater with which the repeater attendant's telephone set comprised in Fig. 2 is adapted to cooperate; and Fig. 10 shows a 21-type 50 repeater circuit with which the telephone set is adapted to cooperate.

In Fig. 1, a line section 11 having a balancing network 12 is connected to a line section 13 having a balancing network 14 by a 22-type repeater comprising an East 55 amplifier 15 having a three-winding or conjugate output transformer, or hybrid coil, 16, and a West amplifier 17 having a similar three-winding output transformer or hybrid coil 18. The amplifiers may be of the three-electrode electron discharge type, or of any other suitable type. In addition to the usual three-windings, that is, primary winding 16', line winding and network winding, transformer 16 has a fourth winding 19, and similarly, transformer 18 has, in addition to the line and network windings and the winding 18', a fourth winding 20, the windings 19 and 20 being monitoring windings, corresponding to windings 15 and 14 of my Patent No. 1,523,037, January 13, 1925. The winding 20 has terminals 21 and 22, and the winding 19 has terminals 22 and 23. Terminals 21 and 22 are connected to the tip conductors of monitoring jacks 24 and 25, respectively; 60 and terminal 23 is connected to the sleeve conductors of those jacks. 65

A repeater attendant's telephone set, described presently, terminates in the tip and sleeve conductors of plugs 26 and 27 which 70 are for insertion in jacks 24 and 25, respectively, when the attendant desires to monitor or talk on the repeater. Should the attendant desire to communicate with line section 11 directly, he will insert the plugs 26 and 75 27 in jacks 28, whereupon proper circuits may be established as described hereinafter. Similarly, proper circuits for communicating directly with line 13 may be established 80 when the plugs 26 and 27 have been inserted 90 in jacks 29.

The attendant's telephone set terminating in the plugs 26 and 27 comprises a receiver 30 connected to the sleeve conductors of plugs 31 adapted for insertion in jacks 32, a 95 transmitter 33 connected to the tip conductors of plugs 31, a transformer 34, a monitoring key 35, a talking key 36, and a ringing key 37. Ringing current sources 38 and 39, of for instance 20 cycles per second 100 and 133 cycles per second, respectively, are provided.

The operation of the system is as follows: With plugs 26 and 27 inserted in jacks 24 and 25, and plugs 31 inserted in jacks 32, but with the system otherwise in the condition shown in Fig. 1, the system is in the condition indicated in Fig. 2. That is, without the operation of any keys, or with the keys in their normal positions, the set is arranged for amplified monitoring in both directions.

The amplified monitoring of transmission passing from line section 11 to line section 13 is over the following circuits: From line 11 current flows through amplifier 15, and the primary winding of transformer 16, inducing an E. M. F. in monitoring winding 19, which causes current to flow over a circuit which may be traced from terminal 23 through sleeve conductors of jack 24 and plug 26, conductor 40, break contact of key 36, conductor 41, key 35, conductor 42, key 36, conductor 43, the entire high impedance winding 44 of transformer 34, conductor 45, break contact of key 35, conductor 46, key 36, conductor 47, right and left hand contacts of key 37, tip conductors of plug 26 and jack 24, monitoring winding 20, to monitoring winding 19. The flow of this current through the high impedance winding 44 of transformer 34 induces in its low impedance winding 48, an E. M. F. which causes current to flow over a circuit which may be traced from the upper terminal of winding 48 through condenser 49, conductor 50, break contact of relay 51, conductor 52, sleeve conductors of upper jack 32 and plug 31, receiver 30, sleeve conductors of lower plug 31 and jack 32, conductors 53 and 54, contact of relay 51, and conductor 55, to the lower terminal of winding 48.

The amplified monitoring of transmission from line section 13 to line section 11 in this circuit condition of the telephone set, is over the following circuits: From line 13 current flows through amplifier 17 and winding 18' of transformer 18, inducing E. M. F. in the monitoring winding 20, which causes current to flow through winding 44 of transformer 34 over the circuit traced above which extends through that winding and windings 20 and 19 all in series. The flow of current in winding 44 induces in winding 48 an E. M. F. which causes energization of receiver 30 over the circuit traced above between winding 48 and the receiver.

In monitoring with the circuit condition indicated in Fig. 2, the connection of the monitoring windings in series with each other will not result in singing or in feed back of energy through those windings from the output of an amplifier to its input; for the input circuit of repeater 15 is in conjugate relation to winding 20, the input circuit of repeater 17 is in conjugate relation to winding

19, and the impedance of winding 44 is high enough to maintain the energy transfer between windings 19 and 20 sufficiently low to prevent any undue amount of feed back from the output to the input of an amplifier through those windings from being caused by the unbalance encountered, in practice, at the hybrid coils 16 and 18.

If now, key 35 be moved from its normal position to operate its right hand contacts, amplified monitoring of only the transmission from line 13 to line 11, that is, the westwardly directed transmission, will be received, the system being then conditioned as indicated in Fig. 3; or, if, on the other hand, key 35 be moved from its normal position to operate its left-hand contacts, amplified monitoring of only the transmission from line 11 to line 13 will be received, the system being then conditioned as indicated in Fig. 4.

Supposing the right-hand contacts of key 35 thus operated, the amplified monitoring of East to West transmission is over the following circuits: From line 13 current flows through amplifier 17 and winding 18' of transformer 18, inducing in monitoring winding 20 an E. M. F. which causes current to flow over a circuit which may be traced from terminal 22 through the tip contacts of jack 25 and plug 27, left and right hand contacts of key 37, conductor 56, break contact of key 36, conductor 57, right hand contact of key 35, and thence over the circuit traced above through conductor 42, key 36, conductor 43, the whole of winding 44 of transformer 34, conductor 45, keys 35, 36 and 37, plug 26 and jack 24 to terminal 21 of winding 20. The flow of current through the winding 44 of transformer 34 induces in its winding 48 an E. M. F. which causes energization of receiver 30 over the circuit traced above between winding 48 and the receiver.

Supposing, on the other hand, the left hand contacts of key 35 are operated, so that as mentioned above, the system is conditioned as indicated in Fig. 4, then the above mentioned amplified monitoring of west-to-east transmission takes place over the following circuits: From line 11 current flows through amplifier 15 and primary winding of transformer 16, inducing in monitoring winding 19 an E. M. F. which causes current to flow over a circuit extending from terminal 22 through jack 25, plug 27, key 37, conductor 56, break contact of key 36, conductor 57, make contact of key 35, conductor 45, the whole of the high impedance winding of transformer 34, conductor 43, break contact of key 36, and thence through the circuit traced above between terminal 23 and the last mentioned contact. The flow of current through winding 44 of transformer 34 induces in its winding 48 an E. M. F. which

causes energization of receiver 30 over the circuit traced above between winding 48 and the receiver.

With plugs 31 in jacks 32, if key 36 is moved to operate its right hand contacts relays 51 and 60 operate; and if keys 35 and 37 be in their normal positions and plugs 26 and 27 be in jacks 24 and 25, the operation of these relays, in conjunction with the 10 operation of the right hand contacts of key 36, arranges the circuits as indicated in Fig. 5, for talking and amplified receiving in both directions simultaneously, over circuits traced presently. Then, by moving key 15 35 to operate its right hand contacts, talking and amplified receiving may be obtained with respect to line 11 only, over circuits traced presently, the circuit conditions being as indicated in Fig. 6; or, on the other 20 hand by moving key 35 to operate its left hand contacts, instead of its right hand contacts, talking and amplified receiving may be obtained with respect to line 13 only, over circuits traced presently, the circuit conditions being then as indicated in Fig. 7. The circuit when arranged as indicated in 25 Fig. 5 operates in the same general manner as the circuit of Fig. 1 of G. A. Campbell Patent 1,254,472, January 22, 1918, the impedances of the line and auxiliary resistance of the patent, however, having their places taken by the impedances presented by windings 20 and 19 of the applicant's drawings, and, further, the applicant employing a 30 resistance 92 in shunt to receiver 30, for a purpose explained hereinafter.

The operation of the right hand contacts of key 36, as mentioned just above, connects ground to conductor 61 at right hand 35 contact of key 36, thereby energizing relay 51 over a circuit from ground through conductors 61 and 62, winding of the relay, and battery 63, to ground; and the operation of the left hand contact of relay 51 energizes relay 60 by connecting the above 40 mentioned ground at the right hand contact of key 36 to grounded battery 64, through conductors 61 and 62 and the winding of relay 60. The use of the relay 60 avoids objectionable clicks in receiver 30, due to 45 operating key 36. The operation of relay 51 also energizes transmitter 33 over a circuit from ground through battery 65, choke coil 66, conductor 67, middle right hand armature of relay 51, conductor 68, tip conductors of upper jack 32 and plug 31, transmitter 33, tip conductors of lower plug 31 and jack 32 to ground. The operation of the 50 right hand inner and outer armatures of relay 51 disconnects the circuit of condenser 49 and winding 48 of transformer 34 from the receiver 30 and connects that circuit across the transmitter. The alternating current circuit for the transmitter is then 55 from ground through right hand make con-

tact of relay 51, conductor 55, winding 48 of transformer 34, condenser 49, conductor 50, make contact of relay 51, conductor 67, make contact of relay 51, conductor 68, tip conductors of upper jack 32 and plug 31, transmitter 33, tip conductors of lower plug 31 and jack 32, to ground. The high impedance winding 44 of transformer 34 has an end terminal 76, tap conductors 77, 78 and 79 and an end terminal 80; and the operation of relay 60 connects the tap conductor 78 directly to the sleeve conductor of upper jack 32, and thence through the sleeve conductor of upper plug 31 to one terminal of receiver 30. Preferably, the number of turns between tap conductors 77 and 78 is equal to the number between tap conductors 78 and 79.

With the system of Fig. 1 in the condition indicated in Fig. 5, the keys 35 and 37 being in their normal positions and the right hand contacts of key 36 being operated, currents sent through winding 48 of transformer 34 from transmitter 33 over the circuit traced just above, cause energization of windings 19 and 20 over a circuit from tap conductor 77 through conductor 81, contact of key 35, conductor 82, contact of key 36, conductor 47, right and left hand contacts of key 37, tip conductors of plug 26 and jack 24, terminal 21, winding 20, winding 19, terminal 23, ring conductors of jacks 24 and 25 and plugs 26 and 27, conductor 40, make contact of key 36, conductor 83, break contact of key 35, and conductor 84, to tap conductor 79. The currents thus produced in winding 20 from transmitter 33 cause corresponding currents in line section 11 and network 12, and also cause currents in winding 18' and output circuit of amplifier 17, but do not cause an E. M. F. to be applied to the input of amplifier 15 since the input circuit of amplifier 15 is conjugate to the winding 20. Similarly, the currents produced in winding 19 from transmitter 33 cause corresponding currents in line section 13 and net work 14, and in winding 16' and output circuit of amplifier 15, but not in the input circuit of amplifier 17. Thus, currents from the transmitter are sent over both line sections 11 and 13 simultaneously.

With the system in the condition indicated in Fig. 5, as just referred to amplified receiving of transmission passing from line section 11 to line section 13 will be obtained over the 120 following circuits: Waves from line 11, transmitted through amplifier 15 and winding 16', induce in winding 19 an E. M. F. which sends current over a circuit from terminal 23 through sleeve conductors of jack 24 and 25 and plugs 26 and 27, conductor 40, make contact of key 36, conductor 83, break contact of key 35, conductor 84, tap conductor 79, and part of winding 44 of transformer 34 to tap conductor 78, whence the cir- 125 130

cuit continues through two branches in parallel with each other. One of these branches is through the contact of relay 60, conductor 52, sleeve conductors of upper jack 32 and 5 plug 31, receiver 30, sleeve conductors of lower plug 31 and jack 32, conductors 53, 85, 86 and 87, right and left hand contacts of key 35, conductors 88 and 89, and key 36, to conductor 90. The other of the two parallel branches extending from tap conductor 78 is through conductor 91, a resistance 92, right and left hand contacts of key 35, conductor 93, and key 36 to conductor 90. From the latter conductor, the circuit for 15 the current of the two branches extends through conductor 56, right and left hand contacts of key 37, tip contacts of plug 27 and jack 25, terminal 22, and winding 19. This current flowing in the part of the winding 44 of transformer 34 between tap conductors 79 and 78, induces an E. M. F. in the 20 part of that winding between tap conductors 77 and 78, and consequently tends to cause current to flow through a circuit extending 25 as follows: From tap conductor 78 over the circuit just traced (including receiver 30 and resistance 92, in parallel) to terminal 22, thence through winding 20, terminal 21, tip conductors of jack 24 and plug 26, left and 30 right hand contacts of key 37, conductor 47, make contact of key 36, conductor 82, break contact of key 35, conductor 81, tap conductor 77 and the part of the winding 44 of transformer 34 included between tap conductors 77 and 78. However, this tendency for 35 this current to flow is neutralized by the voltage drop produced across receiver 30 and resistance 92 by the current from coil 19. The current flowing from winding 19 40 through the part of transformer 34 between taps 79 and 78 induces in winding 48 a current which flows over the circuit traced above through transmitter 33, condenser 49 and winding 48. As may be seen from consideration 45 of the applicant's system with equation (8) on page 5 of the Campbell patent mentioned above, the condition that the winding 20 be connected to points of equal potential with respect to an electro-motive 50 force applied from winding 19 to terminals 22 and 23, requires a certain ratio between the impedance facing the low impedance winding of transformer 34 and the impedance facing terminal 22 and tap conductor 78 55 from the direction of receiver 30, provided the windings of transformer 34 are fixed. Moreover, the impedance facing terminal 22 and tap conductor 78 from the direction of receiver 30 should be of such value that the 60 conjugacy just mentioned obtains throughout the range of the frequencies received by winding 19. The resistance 92 serves to maintain this impedance more nearly at this value than would the impedance of merely the telephone receiver, which ordinarily

varies considerably with frequency. The input circuit of amplifier 15 is conjugate to the winding 20, and therefore any current appearing in winding 20 because of failure to completely realize the other condition of conjugacy just referred to, will reach the input of amplifier 15 only in greatly diminished amplitude. 70

The operation of the system to give amplified receiving of transmission passing from line section 13 to line section 11, the circuits of the system being in the condition indicated by Fig. 5, is similar to the operation, just described, for amplified receiving of transmission passing from line section 11 to line section 13, and the circuits involved may be traced as follows: Waves from line 13, transmitted through amplifier 17 and winding 18', induce in winding 20 an E. M. F. which sends current over a circuit traced above between terminal 21 and tap conductor 77, current continuing through the part of the high impedance winding 44 of transformer 34 included between tap conductors 77 and 78, and thence over a circuit traced above between tap conductor 78 and terminal 22 including receiver 30 and resistance 92 in parallel, the circuit for this current continuing thence through winding 20 back to terminal 21. For reasons made apparent by the above description of the operation of obtaining amplified receiving of transmission passing from line 11 to line 13, no current should flow in winding 19 when amplified receiving of transmission passing from line 13 to line 11 is being obtained as just described, and any such current appearing in winding 19 as a result of improper adjustment of the circuits will reach the input of amplifier 17 only in greatly diminished amplitude, since the winding 19, line winding and network winding of transformer 16 render the input circuit of amplifier 17 conjugate to the impedance facing winding 19 from terminals 22 and 23. 90

In the above description of the operation in transmitting from transmitter 33 to both line sections simultaneously, with the circuits of the system in the condition indicated in Fig. 5, no mention was made of the receiver. The circuits of the receiver having now been traced, it will be apparent that in that sending operation, the receiver is in anti-side tone relation to the transmitter, as is indicated in Fig. 5. This relation results from the facts that the impedance facing terminals 21 and 22 from winding 20 is equal to the impedance facing terminals 22 and 23 from winding 19, and that the current produced in the low impedance winding 48 of transformer 34 by transmitter 33 induces equal E. M. F.'s in the two parts of the winding 44 between tap conductors 77 and 78 and tap conductors 78 and 79. Reference may be had to the Campbell patent mentioned above for a detailed discussion of 100

110

115

130

the theory underlying the anti-side tone relationship in circuits of this general character. The circuit arrangement indicated in Fig. 5 of this application is like the circuit arrangement disclosed in my patent mentioned above, except that the patent discloses no element corresponding to the resistance 92 of this application.

As noted above, with the system in the condition indicated in Fig. 5 as just described, the repeater attendant can arrange the circuit in the manner indicated in Fig. 6 by moving key 35 to operate its right hand contacts. That is, the circuit condition represented in Fig. 6 is obtained when key 37 is in its normal position, the right hand contacts of key 36 are operated, and the right hand contacts of key 35 are operated, with plugs 26 and 27 in jacks 24 and 25 and with plugs 31 in jacks 32. As noted above, this is the circuit arrangement employed by the attendant for talking and amplified receiving, with respect to line 13 only. The operation in talking is as follows: Currents from transmitter 33 energize the low impedance winding 48 of transformer 34 over the energizing circuit traced above between those elements. Consequently, there is induced in the portion of the high impedance winding 44 of transformer 34 between tap conductors 78 and 79 an E. M. F. which sends current through winding 19 over a circuit extending from tap conductor 79 through conductor 84, key 35, conductor 83, key 36, conductor 40, sleeve conductors of plugs 26 and 27 and jacks 24 and 25, terminal 23, winding 19, terminal 22, tip conductors of jack 25 and plug 27, left and right hand contacts of key 37, conductors 56 and 90, make contacts of key 36, conductors 89 and 88, break contact of key 35, make contact of key 35, conductors 94 and 91, tap conductor 78, and the portion of the high impedance winding 44 of transformer 34 between taps 78 and 79. This current in winding 19 induces E. M. F.'s in the line and network windings of transformer 16 which cause current to flow in line section 13 and network 14, but not in the input circuit of amplifier 17 and thence through amplifier 17 and windings 18' and 20 to receiver 30, since, as pointed out above, the input circuit of amplifier 17 is conjugate to winding 19. Thus, in this condition of the circuit of the system the transformer 16 causes the receiver to be in anti-side tone relation to the transmitter. The current in winding 19 of course induces in winding 16' an E. M. F. which causes current to flow in the output circuit of amplifier 15. In this condition of the circuits of the system, amplified receiving from line section 13 may take place as follows: Waves from line section 13 are transmitted through amplifier 17 and winding 18', inducing in winding 20 an E. M. F.

which causes current to energize receiver 30 over a circuit extending from terminal 21 through tip conductors of jack 24 and plug 26, left and right hand contacts of key 37, conductor 47, make contact of key 36, conductor 82, make contact of key 35, sleeve conductors of lower jack 32 and plug 31, receiver 30, sleeve conductors of upper plug 31 and jack 32, conductor 52, contacts of relay 60, conductors 91 and 94, make contact of key 35, conductor 95, break contact of key 35, conductors 88 and 89, make contacts of key 36, conductors 90 and 56, right and left hand contacts of key 37, tip conductors of plug 27 and jack 25, terminal 22, and winding 20, to terminal 21. Of course, waves from line section 13 also induce E. M. F.'s in windings 16' and 19, the E. M. F. in winding 16' causing current to flow in the output circuit of amplifier 15, and the E. M. F. in winding 19 causing current to flow in the circuits just traced between transmitter 33 and winding 19. As noted above, the circuit condition indicated in Fig. 7 is obtained when key 37 is in its normal position, the right hand contacts of key 36 are operated, and the left hand contacts of key 35 are operated, and this is the circuit arrangement employed by the attendant for talking and amplified receiving with respect to line section 11 only. The operation in talking is as follows: Currents from transmitter 33 energize the low impedance winding 48 of transformer 34 over the energizing circuit traced above between those elements. Consequently there is induced in the portion of the high impedance winding 44 of transformer 34 between tap conductors 77 and 78 an E. M. F. which sends current through winding 20 over a circuit extending from tap conductor 77 through conductor 81, key 35, conductor 82, key 36, conductor 47, right and left hand contacts of key 37, tip conductors of plug 26 and jack 24, terminal 21, winding 20, terminal 22, tip conductors of jack 25 and plug 27, left and right hand contacts of key 37, conductor 56, key 36, conductors 89 and 88, make contact of key 35, conductor 91, tap conductor 78, and the portion of the high impedance winding 44 of transformer 34 between tap conductors 78 and 77. This current in winding 20 induces E. M. F.'s in the line and network windings of transformer 18, which cause currents to flow in line section 11 and network 12, but not in the input circuit of amplifier 15, since, as pointed out above, that circuit is conjugate to winding 20. Thus, in this condition of the circuits of the system the transformer 18 causes the receiver to be in anti-side tone relation to the transmitter. The current in winding 20 of course induces in winding 18' an E. M. F. which causes current to flow in the output circuit of amplifier 17. In this condition of

the circuits of the system, amplified receiving from line section 11 may take place as follows: Waves from line section 11 are transmitted through amplifier 15 and winding 16', inducing in winding 19 an E. M. F. which causes current to energize receiver 30 over a circuit extending from terminal 23 through sleeve contacts of jacks 24 and 25 and plugs 26 and 27, conductor 40, 5 make contact of key 36, conductor 83, make contact of key 35, conductors 85 and 53, sleeve contacts of lower jack 32 and plug 31, receiver 30, sleeve contacts of upper plug 31 and jack 32, conductor 52, contacts of relay 60, conductor 91, make contact of key 35, conductors 88 and 89, key 36, conductors 90 and 56, right and left hand contacts of key 37, tip conductors of plug 27 and jack 25, terminal 22 and winding 19, to terminal 23. Of course, waves from line section 11 also induce E. M. F.'s in windings 18' and 20, which cause currents in the output circuit of amplifier 17 and in transmitter 33.

When the repeater attendant desires to communicate with a line section 11 or 13 directly instead of through transformers 16 and 18, he inserts plugs 26 and 27 in jacks 28 or 29 and moves key 36 to operate its left hand contacts, with keys 37 and 35 25 in their normal positions. Upon such operation of key 36, conductor 62 is grounded through conductor 97, in a manner corresponding to that in which conductor 62 was grounded through conductor 61 when the 30 right hand contacts of the key were operated as described above. Assuming that it is line section 13 with which communication is desired, the plugs are inserted in jacks 29. The circuit will then be as indicated 35 in Fig. 8, except that in Fig. 8 the plugs are shown as merely positioned for insertion in the jacks but not inserted therein. With the plugs inserted, the operation of the system in transmitting from transmitter 40 33 to line section 13 is as follows: Currents from transmitter 33 energize the low impedance winding 48 of transformer 34 over the energizing circuit traced above between those elements. Consequently there is induced in the high impedance winding 44 of 45 the transformer an E. M. F. which causes current to flow to the line section 13 over a circuit extending from terminal 78 through a part of winding 44 to terminal 76 and thence 50 through conductor 45, break contact of key 35, conductor 46, break contact of key 36, right and left break contacts of key 37, tip conductors of plug 26 and upper jack 29, line section 13, tip conductors of lower jack 55 29 and plug 27, left and right contacts of key 37, conductor 56, make contacts of key 36, and thence through two branches to tap conductor 78. One of these branches is 60 through conductor 43 to terminal 80 and through part of winding 44 to terminal 78. 65

The other branch is through conductors 96, and 88, left and right break contacts of key 35, conductors 87, 86, 85, and 53, sleeve conductors of lower jack 32 and plug 31, receiver 30, sleeve conductors of upper plug 31 and jack 32, conductor 52, contacts of relay 60, and conductor 98, to tap conductor 78. However, substantially no current flows in this latter branch, since it is conjugate to the transmitter, the portion of winding 44 between terminal 80 and tap conductor 79 having included therein resistance of such value as to approximately balance the impedance of line section 13. This anti-side tone arrangement of the system, as indicated in Fig. 8, is similar to the circuit arrangement of Fig. 4 of the Campbell patent mentioned above. However, in the applicant's Fig. 8, the resistance for balancing the line resistance preferably does not extend within the part of winding 44 included between tap conductors 79 and 78, since that part is to be employed in the circuit arrangements indicated in Figs. 5 and 6 in which it is preferably substantially free from resistance. It should be noted, however, that the resistance of the part of winding 44 included between terminal 80 and tap conductor 79 is in circuit when the system is conditioned as indicated in Figs. 2, 3 and 4 and that the resistance then assists in reducing the transmission loss due to monitoring, and also, that, since the resistance increases the impedance of winding 44, in the circuit arrangement indicated in Fig. 2, it assists in preventing any undue amount of feed back from the output to the input of an amplifier, in the manner pointed out above in the description of the operation of that circuit arrangement. In the circuit arrangements indicated in Figs. 2, 3 and 4, the transmission loss caused by monitoring is further reduced by reason of the fact that the entire winding 44 is in circuit, so that the ratio of the effective turns in winding 44 to the turns in winding 48 is greater than when the circuit is conditioned as indicated in Figs. 5, 6 and 7. It is especially important that this loss be small when each of a large number of repeaters in tandem in a line is provided with monitoring apparatus. Otherwise simultaneous monitoring at a large number of the repeaters might cause the total transmission loss due to monitoring to be excessive. With the circuit arrangements indicated in Figs. 5 to 7, the number of turns of winding 44 included in circuit is such as to give the proper impedance relations for efficient transmission from transmitter 33 through transformers 34, 16 and 18 to line sections 13 and 11, as well as the proper impedance relations for anti-side tone transmission as described above. With the circuit arrangement indicated in Fig. 8 the ratio of the effective 13

primary and secondary turns of transformer 34 is such as to give efficient transmission from transmitter 33 and transformer 34 directly to the impedance of line 13 augmented by the resistance in winding 44.

From the explanation above of the operation of the circuit arrangement indicated in Fig. 5 in receiving from a line section through an amplifier, with receiver 30, the 10 operation of the circuit arrangement indicated in Fig. 8 in receiving directly from a line section, with receiver 30, will be apparent without further explanation. This 15 last mentioned operation is in accordance with the operation indicated at Fig. 3 of the Campbell patent mentioned above.

With plugs 26 and 27 in jacks 28 or 29 of a line arranged for, say 20 or 133 cycle ringing, operation of key 37 in one direction or the other will send ringing current of the proper frequency out on the line, over circuits obvious from inspection of the drawing, operation of the left hand contacts of key 37 sending out say 20 cycle current from source 38, and operation of the right hand contacts of key 37 sending out say 133 cycle current from source 39.

Fig. 9 shows a four wire circuit comprising a four wire repeater R and terminating in two two-wire telephone lines 111 and 113. The repeater R comprises a one-way amplifier 115, between a section 101 and a section 102 of one side of the four-wire circuit, for amplifying transmission passing from line 111 to line 113, and also comprises a one-way amplifier 117, between a section 103 and a section 104 of the other side of the four-wire circuit, for amplifying transmission passing from line 113 to line 111. The dotted portions of line sections 101, 102, 103 and 104 indicate that those portions may be of considerable length. Of course, those portions may include other repeaters such as R; and such other repeaters may be provided with supervisory apparatus of the type used at repeater R and described presently. The four-wire repeater is included in the portion of the four-wire circuit which lies between the dot and dash lines A—A and B—B. The four-wire circuit is joined to the terminating two-wire line 113 by hybrid coil or three winding transformer 116 and line balancing network 114 in the usual manner; and is similarly joined to line 111 by the hybrid coil 118 and line balancing network 112. The hybrid coil 116 comprises the usual line and network windings and third or series winding, the latter being designated 116'; and the hybrid coil 118 comprises the usual line and network windings and third or series winding, the latter being designated 118'. An output transformer 116^a, having a primary winding 116^b, a secondary winding 116^c and a third or monitoring wind-

ing 119, is provided for amplifier 115; and a similar output transformer 118^a, having a primary winding 118^b, a secondary winding 118^c and a third or monitoring winding 120, is provided for amplifier 117. Winding 119 is provided with terminals 122 and 123; and winding 120 is provided with terminals 121 and 122. These three terminals are for connecting windings 119 and 120 to jacks such as 24 and 25 shown in Fig. 1, so that these windings and terminals may cooperate with the plugs 26 and 27 and the attached supervisory apparatus of Fig. 1 in the same manner as do terminals 21, 22 and 23, and windings 19 and 20 of Fig. 1.

The elements 111 to 115 and 117 of Fig. 9 are like elements 11 to 15 and 17, respectively, of Fig. 1. Elements 116 and 118 of Fig. 9 are like elements 16 and 18, respectively, of Fig. 1, except that, as shown, elements 116 and 118 embody no monitoring coils corresponding to the coils 19 and 20 of Fig. 1. However, the hybrid coils 116 and 118 assist in preventing feed back from the output to the input of an amplifier through coils 119 and 120, in receiving by receiver 30 under the circuit conditions indicated in Fig. 2, and also prevent speech currents transmitted from transmitter 33 to one of the windings 119 and 120 under the circuit conditions indicated in Figs. 5, 6 and 7, from entering the amplifier input circuit connected to the bridge points of the hybrid coil to which that one winding transmits. The manner in which the hybrid coils 118 and 116 function to accomplish these results is similar to the manner in which as explained above, hybrid coils 18 and 16 accomplish the same functions in the system of Fig. 1 and will be apparent from the drawings, without further explanation.

Likewise, in view of the description above of the operation of the system of Fig. 1 the manner in which the four-wire repeating system of Fig. 9 and the supervisory apparatus of Fig. 1 operate together will be apparent from the drawings, without further explanation. In the circuit condition indicated in Fig. 5, the impedance of one of the windings 119 and 120 balances the impedance of the other to render receiver 30 anti-side tone with respect to transmitter 33.

The action of resistance shunt 92 in reducing undesired energy transfer between the lines in the two directions has special utility in a four-wire repeating system, since a prime object in employing a four-wire rather than a two-wire circuit is avoidance of the echo current paths introduced by each repeater in a two-wire system.

Fig. 10 shows how the supervisory apparatus of Fig. 1 may be employed with a 21-type repeater 215, connecting telephone lines 211 and 213, and comprising an amplifier 215 and a hybrid coil 216 which has, in ad-

dition to the line windings and the winding 216', a fourth or monitoring winding 219. A resistance 299, having an impedance equal to that presented by winding 219 is connected between terminals 221 and 222, instead of a second monitoring winding such as winding 20 of Fig. 1 or winding 120 of Fig. 9. Winding 219 has terminals 222 and 223. The terminals 221, 222 and 223 are for connection to jacks such as 24 and 25, so that the winding 219 and resistance 299 can cooperate with the plugs 26 and 27 and the attached supervisory apparatus of Fig. 1 in a manner similar to that in which do the windings 19 and 20 or the windings 119 and 120.

However, when the supervisory apparatus of Fig. 1 is applied to the repeater of Fig. 10, the circuit conditions indicated in Fig. 3, and the combination of key positions requisite for that condition, are not employed, since Fig. 10 has no monitoring winding corresponding to winding 20; and with the combination of key positions requisite for the circuit conditions indicated in Fig. 6, there can be no reception by receiver 30, and transmission is to both line sections 211 and 213 instead of to only section 213; and with the key positions corresponding to Fig. 7 there can be no transmission from transmitter 33 to either line section 211 or 213, and reception is from either line section 211 or 213, through amplifier 215, instead of from only line section 211; and with the key positions corresponding to Figs. 2, 4 and 5, winding 219 gives amplified monitoring of transmission in either direction over line sections 211 and 213; and with the key positions corresponding to Fig. 5, winding 219 gives transmission to both line sections 211 and 213. The operation of the repeater of Fig. 10 in connection with the supervisory apparatus of Fig. 1 will be apparent without further explanation, in view of the description above of the operation of the system of Fig. 1.

The broad features involving the general principle herein disclosed may be embodied in many organizations widely different from those specifically shown and described without departing from the spirit of the invention defined in the appended claims.

What is claimed is:

1. A two-way transmission system comprising two transmission sections, means including a repeater connected between said sections, a receiver, a transmitter, and means connecting said transmitter for transmission to one only of said sections at a time, while connecting said receiver for monitoring transmission passing from said one section to the other, after said transmission has been amplified by said repeater.

2. A two-way transmission system comprising two transmission sections, means including a repeater connected between said sections, a receiver, a transmitter, and means

connecting said transmitter for transmission to one only of said sections at a time, with said receiver in anti-side tone relation to said transmitter, while connecting said receiver to receive through said repeater a portion of transmission approaching said repeater over said one section and passing to said other section. 70

3. In combination, two line sections, a repeater, two transformers connecting said repeater to said sections, a receiver, a transmitter, and means, comprising said transformers, connecting said transmitter for transmission to one only of said sections at a time and with one of said transformers 80 preventing said transmission from reaching said receiver, while said means connects said receiver to receive through said repeater transmission approaching said repeater over said one section. 85

4. A two-way transmission system comprising two transmission sections, means including a repeater connected between said sections, a receiver, a transmitter, means connecting said transmitter for transmission to one only of said sections at a time, while connecting said receiver for monitoring transmission passing from said one section to the other, after said transmission has been amplified by said repeater, and means 95 for selecting the section to and from which said transmission and reception are to occur.

5. The method of operation on a system having two oppositely directed unidirectional amplifying elements for amplifying transmission between two sections of a circuit, which comprises introducing transmission into the system at the output side of only one of said elements at a time, for passage 100 over said section to which said output side is connected, and abstracting from said system at the output side of said other element a portion of transmission passing through the latter element to said other section. 110

6. In combination, a receiver, a transmitter, a transformer having two windings, and means for adjusting the impedance ratio of said transformer to one value and connecting the transmitter to transmit through 115 said transformer in the direction from one winding to the other with said transformer so adjusted, and for adjusting the impedance ratio of said transformer to a different value and connecting said receiver to receive, from said transformer, transmission passing through said transformer in the direction from said other winding to said one winding, with said ratio at the second mentioned value. 120

7. In combination, a receiver, a transmitter, a transformer having two windings, and means for adjusting the impedance ratio of said transformer to one value and connecting the transmitter in anti-side tone relation 125 to

with the receiver to transmit through said transformer in the direction from one winding to the other with said transformer ratio so adjusted, and for adjusting the impedance

ing means, and means for changing the connections of the receiver from one side to the other of said impedance changing transformer.

5 ratio of said transformer to a different value and connecting said receiver to receive, from said transformer, transmission passing through said transformer in the direction from said other winding to said one winding,
10 with said ratio at the second mentioned value.

12. In combination, two signaling lines, 70
means for receiving signals from said lines
and transmitting signals to said lines, said
means comprising a receiver, a transmitter
and a non-unity ratio transformer, said
lines being connected to said means in sub- 75
stantially conjugate relation for preventing
the transfer of signals from one of said lines
to the other of said lines through said means,
and means for changing the connections of 80
said receiver from one side to the other of
said impedance changing transformer.

8. In combination, a circuit, a balancing circuit therefor, a repeater, means comprising a transformer connected between said repeater and said circuits, said transformer having a monitoring winding therein, a receiver, a transmitter, a second transformer, said second transformer having windings of different impedances, and means for arranging said transmitter to transmit through said second transformer and the monitoring winding of said first transformer to said circuit, with said receiver operatively connected to a portion of one of the windings of said second transformer, in anti-side tone relation to said transmitter, and for switching said receiver to the other winding of said second transformer and connecting said monitoring winding across at least a larger portion of said one winding of said second transformer than said portion of said one winding to which said receiver was connected.

13. In combination, two signalling lines arranged for transmission of signals from one to the other, means, comprising a transmitter and a receiver in conjugate relation, and comprising a transformer having windings of different impedances, for receiving signals from and transmitting signals to said lines, said lines being connected to said receiving means in substantially conjugate relation for preventing the transfer of energy from one of said lines to the other of said lines through said receiver, and means for changing the connections of said receiver from one winding of said transformer to the other. 85 90 95

9. In combination, two signaling lines, receiving means, comprising a receiver and a transformer having primary and secondary windings, for receiving signals from said lines, said lines being connected to said receiving means in substantially conjugate relation for preventing the transfer of signals from one of said lines to the other of said lines through said receiving means, and means for changing the connections of said receiver from one winding of said transformer to the other.

14. In a two-way signaling circuit, a transmitter and a transformer having windings of different impedances, means for establishing a transmission path for talking from the transmitter through the transformer in the direction from the one of said windings having the lower of said impedances to the other winding, with the receiver operatively connected to a portion of said other winding and means for disconnecting the receiver from said other winding and connecting it to said one winding, whereby the impedance of said receiver as viewed through said transformer is greater than its actual impedance, to receive transmission through said transformer in the direction from said other winding to said one winding. 100
105
110

10. In combination, two signaling lines, two-way repeating means interconnecting said lines, means comprising a non-unity ratio transformer, connected to said lines for receiving signals therefrom, said connections having means for preventing the transfer of signals from one of said lines to the other through said receiving means and for changing the connections of the receiver from one side to the other of said impedance changing transformer.

15. In a two-way signaling circuit, a receiver, a transmitter, a transformer having windings of different impedances, means for establishing a transmission path for talking from the transmitter through the transformer in the direction from the one of said windings having the lower of said impedances to the other winding, with the receiver connected to a portion of said other winding, in anti-side tone relation to said transmitter, and means for disconnecting said receiver from said other winding and connecting it to the opposite side of the transformer, whereby the impedance of said receiver as viewed through said transformer is greater than its actual impedance, to receive transmission through said transformer in the di- 120 125 130

11. In combination, two signaling lines, two-way repeating means interconnecting said lines, means comprising a receiver and
60 a non-unity ratio transformer, for receiving signals from said lines, said lines being connected to said receiving means in substantially conjugate relation for preventing the transfer of signals from one of said lines to
65 the other of said lines through said receiv-

rection from said other winding to the winding of lower impedance.

16. In combination, a transmitter, a receiver, a transformer, said transformer having a relatively low impedance winding with a relatively low number of turns, and having a relatively high impedance winding with a relatively high number of turns and with a relatively high resistance portion and a relatively low resistance portion, and means interconnecting said transmitter, said receiver and said transformer, said means comprising switching means for, at one time, connecting said transmitter to said low impedance winding and connecting said receiver to said high impedance winding in anti-side tone relation to said transmitter and in circuit with a portion of said high impedance winding exclusive of said high resistance, and for, at

10 another time, connecting said transmitter to said low impedance winding and connecting said receiver to said high impedance winding in anti-side tone relation to said transmitter and in circuit with the whole of said 15 high impedance winding, and for, at a third time, connecting said receiver on the low impedance side of said transformer.

17. In combination, a transmitter, a receiver having an impedance varying with 20 frequency, and means connecting said receiver in anti-side tone relation to said transmitter, said means comprising means compensating for the variation in said impedance.

35 18. In a two-way signaling system, a circuit for the transmission and reception of signals, a transmitting circuit proper, a receiving circuit proper, a balancing circuit, and a transformer with a plurality of windings, said elements being so proportioned and related that said first mentioned circuit and said balancing circuit are conjugate, and said receiving circuit proper comprising receiving apparatus having an impedance 40 tending to cause the impedance of said receiving circuit proper to vary with frequency and also comprising an impedance of such character and so related to said apparatus as to reduce said variation.

50 19. In combination, two signaling lines, two-way repeating means interconnecting said lines, and means for receiving signals from said lines, said lines being connected to said receiving means in substantially conjugate relation for preventing the transfer of signals from one of said lines to the other of said lines through said receiving means, and said means comprising a receiver and a resistance shunted there across to reduce the 55 variation of the impedance across said receiver terminals with frequency.

60 20. The method of operating a signaling system including two two-wire circuits and a four-wire circuit connected to said two-wire 65 circuits at points geographically remote from

each other, and a supervisory set including a transmitter and a receiver, which comprises at one time, maintaining said receiver in condition to monitor, on each side of said four-wire circuit, signals passing between said two wire circuits, at the same time preventing transfer of signals between said two sides of said four-wire circuit, and at the same time, maintaining said transmitter in condition to transmit to said four-wire circuit.

70 21. In combination, a four-wire signaling circuit comprising two one-way two-wire lines, means for receiving signals from each of said lines, said lines being connected to said receiving means in substantially conjugate relation for preventing transfer of signals from one of said lines to the other of said lines through said receiving means, and transmitting means for impressing signaling currents on said lines, said transmitting and receiving means being conjugate.

75 22. A monitoring circuit for a four-wire signaling system employing repeater coils, comprising monitoring windings inductively 80 associated with the repeater coils, an operator's substation set comprising a transmitter and a receiver, and connections from said substation set to each of a plurality of said monitoring windings for balancing the impedance of one of said monitoring windings against the impedance of another of said monitoring windings to render said substation set anti-side tone when transmitting 85 from said transmitter.

90 23. A signaling system comprising two transmission lines, a two-way repeater circuit, a network for balancing each of said lines, a transformer for associating one of said lines with one of said networks and 95 said repeater circuit, a second transformer for associating the other of said lines with the second of said networks and said repeater circuits, an auxiliary winding mounted on 100 each of said transformers, a substation set comprising a transmitter, a receiver, a transformer having two windings, connections from said substation set to said auxiliary windings for impressing currents from said 105 transmitter serially upon said windings 110 while preventing side tone in said receiver, and means for changing the connections of said receiver from one winding to the other winding of said last mentioned transformer.

115 24. In combination with a repeating system having a repeater with output transformers and monitoring windings on said transformers, a repeater attendant's telephone set, comprising a receiver and a transmitter, normally arranged for amplified monitoring in both directions, said set comprising a monitoring key operable to one position to give amplified monitoring, through said repeater, in one direction, and operable to another position to give amplified monitoring,

- through said repeater, in the other direction, and said set comprising a talking key operable to connect the transmitter for transmission to said windings with the impedance of one of said windings balanced against the impedance of the other of said winding to render said receiver anti-side tone with respect to said transmitter, said monitoring key and said talking key being operable to 10 arrange said set for talking in either direction, one direction only at a time, with amplified monitoring, through said repeater, of transmission from the direction to which the set is arranged for transmission.
- 15 25. In combination, a four-wire signaling circuit comprising two one-way two-wire lines, a receiving circuit, and means comprising two circuits conjugate to each other connecting said receiving circuit to receive 20 signals from each of said lines, said receiving circuit comprising receiving apparatus having an impedance tending to cause the impedance of said receiving circuit to vary with frequency and also comprising an 25 impedance of such character and so related to said apparatus as to reduce said variation.
26. In combination, a four-wire signaling circuit comprising two one-way two-wire lines and means for receiving signals from 30 each of said lines, said lines being connected to said receiving means in substantially conjugate relation for preventing transfer of signals from one of said lines
- to the other of said lines through said receiving means, and said receiving means comprising a receiver having an impedance varying with frequency and also comprising an impedance of such character and so related to said receiver as to reduce the variation of impedance across the receiver terminals. 35
27. In combination, a four-wire repeater comprising two oppositely directed one-way two-wire repeating paths and a two-way signaling system comprising a circuit connected to one of said paths for the transmission and reception of signals, a transmitting circuit proper, a receiving circuit proper, a balancing circuit connected to the other of said paths, and a transformer with a plurality of windings, said elements being so proportioned and related that said first mentioned circuit and said balancing circuit are conjugate and said transmitting circuit proper and said receiving circuit proper are conjugate, and said receiving circuit proper comprising receiving apparatus having an impedance tending to cause the impedance of said receiving circuit proper to vary with frequency and also comprising an impedance of such character and so related to said receiving apparatus as to reduce said variation. 40 45 50 55 60

In witness whereof, I hereunto subscribe my name this 9th day of February A. D., 1925.

DONALD A. QUARLES.
